UNITED STATES PATENT OFFICE.

DANIEL D. LONDON, OF DETROIT, MICHIGAN, ASSIGNOR OF ONE-HALF TO MORRIS S. RADETSKY, OF DENVER, COLORADO.

ILLUMINATED DISPLAY DEVICE.

Application filed February 11, 1928. Serial No. 253,591.

The present invention relates to illuminated display devices and particularly to devices of this sort intended for the display of perforated license plates for vehicles so that the numbers thereon will be clearly visible both by day and night.

Among the objects of the invention is to simplify and to improve the construction of such devices and to reduce the cost of manufacture and installation.

Other objects will readily occur to those skilled in the art upon reference to the following description and the accompanying drawings, in which:—

15 Figure 1, is a view in elevation of the holder with a suitable license plate therein;

Figure 2, is a section on line 2—2 of Figure 1; and

20 Figure 3, is a section on line 3—3 of Figure 1.

The holder consists of a casing 10 having its back, ends and bottom made integral either by forming a suitable sheet of metal or by securing the proper size plates together by soldering, welding or otherwise.

25 The bottom of said casing will have at its forward edge a groove portion 11 formed by bending the metal in any suitable process, while the side members 12 will be provided with similar grooves 13.

30 The top edge of the rear wall of the casing will be bent forward and turned under upon itself to provide an interlocking portion 14 adapted to cooperate with a similarly turned edge 15 of the top member 16. The groove portion 11 will extend completely across the casing and the groove portions 13 at the sides will preferably extend the full height of the casing.

35 The top member 16 with its interlocking edge 15 will preferably extend beyond the plane of the several grooves 11 and 13 so as to form an overhanging edge 17.

40 It is preferred to mount the casing 10 on a suitable bracket or the body of a vehicle by screws or bolts extending through the back member of the casing so that all of the fastening devices for holding the casing in place will be accessible only from the inside thereof.

45 The perforated license plate 20 shown clearly in Figure 1 will preferably be of rather thin material and of such size as to fit in the grooves 11 and 13 so as to extend to the bottom thereof and in the bottoms of

the grooves it is preferred to place a strip of felt or other cushioning material 21. Also adapted to fit in these grooves upon the felt 21, is an opalescent or semi-transparent plate 22 preferably of glass.

50 After the plates 20 and 22 have been inserted in the grooves, the cover member 16 will be slipped on from one end of the casing with the portions 14 and 15 interlocking and this will be secured against removal 55 by means of a screw 30 extending through one end of the cover 16 and a suitable lug on the upper end of one of the end portions 12.

55 With a suitably colored plate 22 behind 70 the perforated license plate, it will be possible to readily observe the numbers in the plate 20, it being, of course, obvious that the surface of plate 20 shall be of some contrasting color.

75 In order to be able to distinguish the numbers in the plate at night, the casing will be provided with illuminating means, such as is shown clearly in Figures 2 and 3. This illuminating means consists of a horizontally placed double end socket 35 having in each end an electric bulb 36 and to which current is supplied through a suitable lead wire 37 passing through the back of the casing 10 and prevented from fraying by ferrule 80 member 38. The socket may be mounted on the back of the casing 10 upon a bracket 39 and is preferably of such length as to space the bulbs several inches apart.

85 It is preferred to use in the present device a plate 22 of white opalescent glass and to use bulbs 36 of some suitable color, although white bulbs and a colored plate 22 may be used, if desired.

90 Now having described the invention and the preferred form of embodiment thereof it is to be understood that the same is to be limited not to the specific details herein set forth but only by the scope of the claims which follow.

100 I claim:—

1. A license plate holder comprising a casing having grooves along its side edges and bottom edge and adapted to retain therein a perforated license plate and a suitable 105 semi-transparent backing plate, said casing being open at its top and provided along the rear edge thereof with means adapted to interlock with a cover member, a cover member for the same provided with means 110

adapted to interlock with the before mentioned interlocking means, and means for securing said cover in place.

2. A license plate holder comprising a rectangular casing open at its front and top, grooves along the bottom and sides of the front for holding a license plate therein, a cover for said casing, interlocking means to hold said cover in place upon the casing, a plurality of electric lights in said casing, and means for supplying electric current thereto.

DANIEL D. LONDON.
